UNITED STATES PATENT OFFICE.

CHARLES G. WILLSON, OF READING, PENNSYLVANIA.

DESIGN FOR A BADGE.

SPECIFICATION forming part of Design No. 31,387, dated August 15, 1899.

Application filed July 14, 1899. Serial No. 723,840. Term of patent 7 years.

To all whom it may concern:

Be it known that I, CHARLES G. WILLSON, a citizen of the United States, residing at Reading, in the county of Berks and State of Pennsylvania, have invented and produced a new and original Design for a Badge; and I do hereby declare the following to be a full, clear, and exact description of the same, reference being had to the accompanying drawings, forming a part thereof.

This is a design for a badge.

In the drawings, Figure 1 is a front view, and Fig. 2 a top edge view, of my design.

The leading feature of my design is the peculiarly-shaped simitar resting within the crescent. The blade A of the simitar is almost semicircular in form, and its handle

B is formed with fanciful scrollwork. The crescent C is formed with an edge c on its inside and outside diameters, and its tips d are formed with scrollwork. The blade A of the simitar partially hides one side of the crescent C.

Having thus fully described my new and original design, what I claim, and desire to secure by Letters Patent, is—

The design for a badge, substantially as herein shown and described.

In testimony whereof I affix my signature in presence of two witnesses.

CHARLES G. WILLSON.
